UNITED STATES PATENT OFFICE.

HORATIO OLIVER WHYMAN, OF PHOENIX, ARIZONA.

COMBINED WRITING DESK AND BLACKBOARD.

Application filed July 15, 1922. Serial No. 575,224.

To all whom it may concern:

Be it known that I, HORATIO O. WHYMAN, a citizen of the United States, residing at Phoenix, in the county of Maricopa and State of Arizona, have invented certain new and useful Improvements in Combined Writing Desks and Blackboards; and I do hereby declare the following to be a full, clear, and exact description of the invention, such as will enable others skilled in the art to which it appertains to make and use the same.

This invention relates to a combination secretary or writing desk and blackboard, and more particularly to one especially designed to be used by children attending school or in the home, but adapted for general use.

Combined blackboards and writing desks as heretofore ordinarily constructed are more or less complex and expensive to make, and are also troublesome to handle or move from place to place, and liable to get out of order, and as a result there is little demand for them.

One object of the invention is to provide a simple, inexpensive and durable combined secretary or writing desk and blackboard composed of few parts assembled in compact form, so that it will occupy very little space when in use, or when packed for transportation, and which at the same time will be serviceable and commercially desirable.

A further object is to provide an article of the character referred to having combined therewith a till and drawer which is adapted to serve the double purpose of a receptacle for money, chalk and writing materials and utensils, and also as a support for the blackboard when it is turned down into position for use as a writing desk.

A further object is to provide a combined blackboard and writing desk that will not only occupy little space but will allow ample room or space below the bottom of the drawer for the knees, so that the "kiddies" can sit comfortably when using the desk.

A further object is to provide a combined secretary-blackboard that has all of the advantages of the two separate articles, at practically the cost of a secretary alone, as heretofore ordinarily constructed, and which is inexpensive in manufacture and may be made and sold at such a low price as to enable the great mass of people to buy and use the same.

The invention will first be hereinafter more particularly described, with reference to the accompanying drawings, which are to be taken as a part of this specification, and then pointed out in the claims at the end of the description.

In said drawings,

Fig. 1 is a perspective view of a combined secretary-blackboard showing the parts in position for use as a secretary or writing desk;

Fig. 2 is a perspective view of the same showing the parts arranged with the blackboard in position for use;

Fig. 3 is a perspective view of the same showing the hinged board in an intermediate position from which it may be raised for use as a blackboard or turned down for use as a writing desk; and

Fig. 4 is a transverse sectional view of the sliding drawer and till.

Referring to said drawings, in which the same reference letters are used to denote corresponding parts in different views, the letters A, A, denote uprights or standards which are preferably tapering toward their upper ends, which are connected by a cross-bar or shelf a and adapted to support there-between below said shelf, transverse supports for a series of sliding drawers B, and pigeon holes C for the storage of paper, pencils, or other articles, while their lower ends are bifurcated to provide legs a¹, a¹.

In suitable guide-ways below said drawers and pigeon holes is fitted a combined drawer and till D, which is designed and adapted to provide a receptacle for chalk, pens, pencils, or other articles. Over the combined drawer and till is pivoted along one of its edges, a swinging leaf or board E, one side or surface of which is provided with a suitable coating or material to form a blackboard, that is the outer side when in a vertical or raised position, the other or inner side being plain or finished so as to adapt it to serve as a writing desk when the board is turned down into a horizontal position. In the latter position this board is firmly supported by the combined drawer and till, which is drawn out for that purpose, and when the board is raised to a substantially vertical position its outer surface is slightly inclined from base to top, away from the till, so that the center of gravity falls rearwardly of its pivotal support, whereby it is sustained in the desired position to provide

100
105
110

a blackboard for the use of a child at school or for other purposes. The board E may be constructed of any suitable material, and if desired may have a glass front, or removable 5 plate of glass on the inner side thereof for use as a writing desk and underneath which designs can be placed from which copies may be made for the amusement or instruction of school children, teachers and others.

10 The combined drawer and till may be made of any desired length and width, and the till can be milled in any suitable length and cut to the length of the inside of the drawer, in which it is fastened by means of 15 ordinary nails inserted through the side pieces of the drawer and driven into the four corners of the till. The till is secured to the front plate d^1 of the drawer, and raised slightly above the sides of the 20 drawer so that when the blackboard is in an upright position and the drawer is moved inwardly the till will contact with the lower edge of the hinged board and serve as a stop to prevent further inward movement of 25 the drawer and till, leaving the till exposed in position for use while the drawer is closed; and when the drawer is drawn out it forms with the till a support for the hinged board E when the latter is lowered into position to provide a desk for writing 30 purposes. The raised part of the drawer and till enables one to make the till in such outline that it will conform to the exact level of the board which it supports. Constructed as 35 described, the combination secretary-blackboard has all of the advantages of a secretary and blackboard as separate articles at practically the cost of the former and is most compact for storage or shipping purposes. By removing the combined till-drawers of two desks or combined secretary-blackboards and placing the two desks one 40 on top of the other, with the tapered end of one and the larger end of the other at 45 each end, the two articles will fill a comparatively small space, as the two till-drawers will just fit in the bottom of the base, and thus a single smooth crate will suffice for crating the two articles without waste of 50 space for two, as would be necessary with a stationary till overlying or above the drawer.

For the sake of economy, all of the parts are made of wood, with suitable fastening 55 means, such as nails or the like for securing the parts together, but metal or other material may be used, and various changes may be made in the details of construction and arrangement of parts without departing 60 from the spirit and scope of my invention, and I therefore do not desire to be limited in the appended claims to the specific construction and arrangement shown and described.

65 Having thus described my invention,

what I claim as new and desire to secure by Letters Patent of the United States is:—

1. A combined writing desk and blackboard comprising a pair of uprights, a swinging blackboard pivotally supported 70 between said uprights in a substantially vertical position and adapted to be lowered into a substantially horizontal position and serve as a writing desk, a drawer slidably fitted between said uprights below said 75 blackboard and a till within said drawer at the front thereof forming therewith a rest for said blackboard when the latter is lowered; said till being adapted to serve as a stop to limit inward movement of the 80 drawer by contact with the lower edge of said blackboard when the drawer is moved inwardly and the blackboard raised.

2. In combination, a pair of standards supporting therebetween a sliding drawer; 85 said drawer carrying a till at the front thereof so as to provide separate receptacles for writing materials, chalk, pencils, etc., and a blackboard hinged between said standards in a substantially vertical position 90 and adapted to swing downwardly to a horizontal position, for use as a writing desk; the lower edge of said blackboard, when raised, projecting into the path of movement of said till so as to adapt the 95 till to serve as a stop to limit inward movement of the drawer when the blackboard is raised.

3. In combination, a pair of uprights having 100 comparatively wide base portions and tapering toward their upper ends, a plurality of sliding drawers and pigeon-holes supported between said upper ends, a hinged blackboard between said uprights arranged 105 to cover said drawers and pigeon-holes and adapted to swing downwardly into a substantially horizontal position and serve as a writing desk; a sliding drawer below said pigeon-holes carrying a till at the front thereof; said till being adapted to serve as a stop to limit inward movement of said 110 drawer and leave the till exposed in usable position when the blackboard is raised and the drawer closed.

4. In combination with a combined writing desk and blackboard, including uprights between which is pivoted along one edge a board adapted to stand upon said edge in a substantially vertical position, to serve as a blackboard, and to be lowered to a substantially horizontal position, to serve as a writing desk, a combined drawer and till 115 slidably supported between said uprights so as to adapt said till to be exposed in position for use when said board is raised and to serve with said drawer as a support for said board when in its horizontal position; the lower edge of said blackboard in its raised 120 position, being arranged in the path of said till so as to stop its inward movement, caus-

ing the till to remain exposed on the outside while the drawer is closed.

5. A combined writing desk and black-board comprising a pair of standards consisting of plain boards having their lower ends bifurcated and tapering toward their upper ends, said ends being rigidly connected together by a cross-piece forming a shelf, spaced cross-pieces under said shelf having partitions therebetween forming a plurality of pigeon-holes and spaces at one side for the insertion of small drawers, a combined sliding drawer and till arranged below said cross-pieces, and a hinged black-board arranged to cover and conceal said

20

pigeon-holes and to swing downwardly into a horizontal position and serve as a writing desk; said combined drawer and till serving as a support for said blackboard when the latter is in a horizontal position, and said till being exposed in usable position when the sliding drawer is closed and the black-board raised.

In testimony whereof I affix my signature in the presence of two witnesses.

HORATIO OLIVER WHYMAN.
